TUNING INDICATOR TUBE

Herbert M. Wagner, Newark, N. J., assignor, by
mesne assignments, to Radio Corporation of
America, New York, N. Y., a corporation of
Delaware

Application June 27, 1935, Serial No. 28,689

7 Claims. (Cl. 250—27.5)

My invention relates to electron discharge devices, more particularly to such devices useful as visual indicators of voltage and having a fluorescent electrode which is rendered luminous and has the appearance of a pattern of light, which may be of constant width and varying length and which changes in response to the change in the magnitude of the applied voltage, a device of this character being particularly useful as a tuning indicator in radio receiving sets. The present invention is an improvement over a device of the general character described and claimed in a copending application of Harry C. Thompson, Serial No. 28,665, filed June 27, 1935 and assigned 15 to the same assignee as the present invention.

It is an object of my invention to provide an electron discharge device of this general character which is particularly suitable for use as a tuning indicator in a radio receiving set in which resonance is indicated by a brilliant luminous glow on the anode, and in which departure from resonance is indicated by a dark space or gap 20 between edges of a luminous pattern of light.

One embodiment of such a device useful as a tuning indicator and described in the Thompson application referred to above comprises an envelope having within it a straight thermionic equipotential cathode provided with two separate emitting sections, one of which is surrounded 25 by amplifier elements which may comprise a control grid and anode, and the other of which is surrounded by the tuning indicator elements of the tube consisting of a straight control electrode parallel to the cathode and an anode coated with fluorescent material which may be concentric 30 with and surrounding the cathode and the control electrode. In operation electrons flow from the cathode to the fluorescent anode with sufficient velocity to bombard the fluorescent anode 35 and render it luminous. The control electrode is connected to the amplifier anode and the tube so connected into a receiving circuit that when the circuit is tuned to resonance with an incoming signal the luminous portion of the plate is 40 of a predetermined width, preferably the device is so connected that the luminous portion of the anode of the tuning indicator portion is of maximum width, the dark portion of minimum width, when the circuit is tuned to resonance, and preferably the entire anode is made fluorescent and 45 the dark portion disappears.

The novel features which I believe to be characteristic of my invention are set forth with particularity in the appended claims, but the invention itself will best be understood by reference 50

to the following description taken in connection with the accompanying drawing in which Figure 1 shows an electron discharge device embodying my invention with parts broken away to show details of construction; Figures 2 and 3 are top views with parts removed to show the tuning indicator portion of the tube and the pattern of light under different voltage conditions; Figures 4 and 5 are top views of modifications of the tuning indicator shown in Figures 2 and 3; 10 Figure 6 is a perspective view of another modification of the electrode construction of the tuning indicator section of a tube made in accordance with my invention; Figure 7 is a circuit diagram embodying a tuning indicator tube made in accordance with my invention.

The electron discharge device or tuning indicator tube shown in Figure 1 comprises an evacuated envelope 10 provided with the usual stem and press 11 and base 12. Supported from the press are a cathode 13, preferably the conventional indirectly heated equipotential type, and a grid 14 concentric and preferably coextensive with and surrounding the cathode, and an anode 15 surrounding the grid. While shown as a 25 triode this portion of the tuning indicator tube could be of any other multi-element type.

In accordance with my invention the tuning indicator elements of the tube are placed at the upper end of the mount. The cathode 13 is extended upwardly and provided with a second emitting section 16 adjacent which is placed the control electrode 17 which may be a rod or a vane shaped from sheet material and placed edge-wise to the cathode. This control electrode 17 is supported from and connected to one of the side rods of the anode 15. Surrounding and concentric with the emitting portion 16 of the cathode is an anode 19 shaped like a dishpan having a collar 20 and a coating 21 fluorescent under 30 electron bombardment. The electrons emitted from the cathode and striking the anode with sufficient velocity, cause it to fluoresce. A cap 22 is positioned over the top end of the cathode 13 to confine the electrons to the emitting portion, the collar 20 preventing electrons from reaching the glass walls of the envelope over the top of the anode. The cap 22 is supported from the dishpan-shaped anode and preferably electrically connected thereto by means of side rods 23 positioned 90° from the control electrode as best shown in Figure 6. The cap 22 also serves as an electrostatic shield to prevent any stray charges that might develop on the glass envelope 55

from affecting the electron beam from the cathode to the fluorescent anode.

In this type of tuning indicator the electrons travel radially outward from the cathode to the fluorescent coating on the anode in a wide beam. The extent of the surface of the anode reached by the electron beam is determined by the voltage on the control electrode 17. The less negative this electrode is with respect to the anode 20, that 10 is the more positive with respect to the cathode 16, the greater the area of the anode covered by the beam and the greater the area of the fluorescent portion of the anode. According to my invention, the control electrode 17 is at a positive 15 potential with respect to the cathode. The advantages of this are that the boundaries of the electron beam are sharp and well defined, there can be a high concentration of electrons at the edges of the luminous areas of the anode so that 20 the edges are brighter and stand out more prominently, a high current to the luminescent anode and hence high luminosity is obtained with low anode voltages, and the control electrode can be coupled directly to an amplifier. I have found 25 also that a tube made in accordance with my invention is not critical to variations in cathode temperature, and that it can also be used with either alternating or direct voltages and currents.

The tube is viewed from the end so that the 30 pattern of light is viewed as shown in Figures 2 and 3. As shown in Figure 2 when the control electrode is at a potential near that of the cathode the anode fluoresces only over the area indicated by the shaded lines. As the electrode becomes 35 more positive more of the surface of the anode fluoresces until at a predetermined voltage the entire surface of the anode 20 fluoresces. This is the pattern which is shown in Figure 3 and which is obtained when the circuit in which 40 the tube is used is tuned to resonance. Under these conditions the edges of the luminescent portion of the fluorescent anode just touch so that the dark space is at its minimum or just disappears. In Figures 4 and 5 are shown the patterns 45 of light obtained when two control electrodes 17' are used instead of one, two separate luminescent portions being obtained. In this arrangement the pattern of light extends around the entire circumference of the anode 20 when the circuit in 50 which the tube is used is tuned to resonance. By depending upon the dark space to indicate voltage conditions, several advantages are obtained over tubes depending only on the width or length of a luminous indication. The range of indication 55 can be made all the way from zero dark space to a maximum gap between bright areas of considerable width thru which the beam edges can move. It is also possible to extend the range by making the control electrode so positive that 60 overlapping of the electron beam results. Where beams overlap the luminosity is increased greatly so that at the overlapping portion the luminosity is very intense. The fluorescent surface of the anode can, therefore, be used more than once 65 so that the range is extended; that is, it can be used once for the gap and again for the overlap. The most important advantage obtained, however, is that the eye is very sensitive to changes in beam width in the neighborhood of zero width; 70 that is, where the beam edges just touch. As a result the tuning of a set in which the tuning indicator tube is used, can be made very precise.

In the modification shown in Figure 6 the control electrode 24 of sheet metal mounted edgewise 75 to the cathode is formed to taper from the top

increasing in width toward the bottom. The control electrode increases in width as the distance between the fluorescent portion of the tuning indicator anode and the cathode decreases due to the sloping side of the anode. By this construction the control of the control electrode is such that the electrons reaching the anode form a sharp straight line at the edge of the luminescent pattern, so that when the pattern of light forms a complete annulus the edges of the pattern meet 10 along a straight line. By making the control electrode of different shapes the edges of the luminescent areas can be given shapes other than straight lines.

In Figure 7, I show a circuit embodying a tube 15 made in accordance with my invention. The anode 15 of the triode section and the anode 19 of the tuning indicator section are electrically connected to each other thru a resistor 25. The fluorescent anode is connected directly to a source 20 of voltage supply 26. When no current flows from cathode 13 there is no voltage drop in resistor 25 and the anode 15 and control electrode 17, which is connected to it, are at substantially the same potential as the anode 19 of the tuning 25 indicator section of the tube. Under these conditions the pattern of light forms a complete annulus as shown in Figure 3, and the anode fluoresces around its entire inner sloping surface. When a current flows in the circuit of the anode 30 15 a potential drop develops across the resistor 25 so that the anode 15 and control electrode 17 are made more negative with respect to the anode of the tuning indicator section of the tube 20, and approaches the potential of the cathode, producing a pattern of light such as indicated in Figure 2, or when two control electrodes are used a pattern such as shown in Figure 4. The magnitude of the current thru the triode portion of the tube is determined by the bias on the control 40 grid 14.

In the circuit shown, a diode detector or rectifier 21 has its anode 28 and its cathode 29 connected to opposite sides of the secondary of the intermediate or radio frequency transformer 32 45 tuned by condenser 36, the cathode being connected thru the resistor 30 and by-pass condenser 31. The cathode side of the transformer 32 is connected to the control grid 14 thru resistor 33, the grid being by-passed by means of by-pass 50 condenser 34 so that a bias is impressed on the grid 14. The conductor 35 may be connected to the automatic volume control circuit. In the arrangement shown with the set untuned and no signal passing thru the transformer 32, no current passes thru resistor 30 and no bias is developed. The grid 14 is at ground potential and permits current to flow thru the triode section of the tube under which conditions the control electrode 17 is at a potential near that of the cathode as described above, the light pattern takes 60 the form shown in Figure 2. With the set tuned to a signal a rectified current passes thru resistor 30 developing a drop across this resistor and impressing a bias on the control grid 14 of the triode 65 thru the resistor 33. This reduces the current passing thru the triode in proportion to the bias impressed upon the grid so that the control electrode 17 becomes more positive with respect to the cathode 13. The constants of the various elements are so chosen that when tuned to resonance the pattern of light is of the greatest width or forms a completely annular form such as shown 70 in Figure 3.

While I have indicated the preferred embodiment 75

ments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is—

1. An electron discharge device having an envelope, a cathode within said envelope for emitting electrons, a dish-shaped anode surrounding said cathode and having its interior surface coated with a fluorescent material for receiving electrons from said cathode to produce a luminous annular shaped pattern on said anode, a control electrode positioned between said anode and said cathode and parallel to the cathode for determining the area of the fluorescent surface of the anode reached by the electrons from said cathode.

2. An electron discharge device having an envelope, a cathode within said envelope for emitting electrons, a dish shaped anode surrounding said cathode and having its interior surface coated with a fluorescent material for receiving electrons from said cathode to produce a pattern of light, a straight rod-like control electrode between said cathode and said anode and parallel to the cathode, and a cup-shaped member positioned over the end of said cathode and cooperating with said dish-shaped member to confine the electrons from said cathode to the surface of said anode.

3. An electron discharge device having an envelope, a cathode within said envelope for emitting electrons, a dish-shaped anode surrounding said cathode and provided with a fluorescent coating for receiving electrons from said cathode, a cup-shaped member positioned over the end of said cathode and electrically connected to said dish-shaped anode for confining the electrons from the cathode to the surface of the anode, and a control electrode positioned between said cathode and anode and comprising a straight rod-like member parallel to the cathode for determining that portion of the surface of the anode reached by electrons from the cathode to cause the anode to fluoresce.

4. An electron discharge device having an envelope, a straight thermionic cathode within said

envelope having two separate emitting sections thereon, a grid and anode surrounding one of said emitting sections and a control electrode adjacent the other emitting section electrically connected to and supported by said anode, and a second anode concentric with and positioned around said other emitting section of the cathode and said control electrode and having a fluorescent coating on the interior thereof, and a cap positioned over one end of said cathode and electrically connected to the coated anode.

5. An electron discharge device having an envelope, a straight thermionic cathode within said envelope having two separate emitting sections thereon, a grid and an anode surrounding one of said emitting sections and a control electrode adjacent the other emitting section electrically connected to and supported by said anode, and a second anode concentric with and positioned around said other emitting section of the cathode and said control electrode, and having a fluorescent coating on the interior surface thereof.

6. An electron discharge device having an envelope, a cathode within said envelope for emitting electrons, a dish-shaped anode surrounding said cathode and having its interior surface coated with a fluorescent material for receiving electrons from said cathode to produce a luminous annular shaped pattern on said anode, a control electrode positioned between said anode and said cathode and parallel to the cathode for producing a dark space on the fluorescent surface of said anode, the size of which changes in response to changes in the voltage applied to said control electrode.

7. An electron discharge device having an envelope, a cathode within said envelope for emitting electrons, a dish-shaped anode surrounding said cathode and having its interior surface coated with a fluorescent material for receiving electrons from said cathode to produce a pattern of light on said anode, a straight rod-like control electrode between said cathode and said anode and parallel to the cathode for producing a dark space on the pattern of light on the surface of the anode which changes in response to changes in voltages applied to said control electrode and a cup-shaped member positioned over the end of said cathode and cooperating with said dish-shaped member to confine the electrons from said cathode to the surface of said anode.

HERBERT M. WAGNER.
